UNITED STATES PATENT OFFICE

125,280

DESIGN FOR AN ANIMAL BED

Earl W. Little, Indianapolis, Ind.

Application October 14, 1940, Serial No. 95,829

Term of patent 14 years

To all whom it may concern:

Be it known that I, Earl W. Little, a citizen of the United States, residing at Indianapolis, in the county of Marion, and State of Indiana, have invented a new, original, and ornamental Design for Animal Beds, of which the following is a specification, reference being had to the accompanying drawing, forming part thereof.

I claim:

The ornamental design for an animal bed, as shown.

EARL W. LITTLE.
